UNITED STATES PATENT OFFICE.

MARTIN ELKOFER, OF LEIPZIG, GERMANY.

FEED-WATER REGULATOR.

1,020,642.

Specification of Letters Patent. Patented Mar. 19, 1912.

Application filed January 11, 1911. Serial No. 601,995.

To all whom it may concern:

Be it known that I, MARTIN ELKOFER, a subject of the King of Prussia, residing at Leipzig, in Germany, have invented a certain new and useful Improvement in Feed-Water Regulators, of which the following is a specification.

This invention relates to feed-water regulators of the class wherein a weighted feed-valve is controlled by a float in a water chamber which is charged and emptied according to the water level in the boiler.

The object of the invention is to accelerate the feed-action on fall of water-level.

The invention is illustrated in the accompanying drawing, in which:—

Figure 1 is a vertical section, showing the controlling apparatus in conjunction with the boiler, the feed-valve being closed. Fig. 2 is a similar view, showing the feed-valve open. Fig. 3 is a plan-view of the valve-actuating lever. Fig. 4 shows a modification of the feed-valve casing on a larger scale.

In the drawing, *a* represents an open vessel or cup, which forms the float and is vertically movable in one leg of the U-shaped float chamber *b*. The cup *a* is joined by a short rod *c* to a lever-arm *d* fixed to a spindle *e* (Fig. 3). To the latter are also fixed lever-arms *f* and *i*, the lever arm *f* being connected to the rod *g* of the feed-valve *h*. The arm *i* is connected to a weight *k* movable in the other leg of the U-shaped chamber *b*. The parts *d*, *f*, *i* may thus be regarded as a double-armed lever fulcrumed at *e*, and having one arm weighted by the cup *a* and the other arm weighted by the weight *k*, the latter arm being connected to the feed valve. The arms *d*, *f*, *i* are made in one piece with the spindle *e*.

A pipe *n* branching from the upper part of the leg containing the cup *a* terminates in the boiler at the average water-level. The floor *l* of the float chamber, between the interior of the latter and the outlet chamber of the feed-valve casing *z*, has a hole *m* controlled by a valve *o* on the valve-rod *g*.

When the water-level in the boiler *x* is normal the pipe *n* and float chamber *b* are filled with water, and the movable parts are in the position shown in Fig. 1, the feed-valve *h* being closed by the pressure exerted by the weight *k*. When the water-level falls so that steam can enter the pipe *n* the chamber *b* is rapidly emptied or partly emptied

of water through the hole *m*, and the cup *a*, which remains filled with water but is no longer buoyed up by water in the chamber *b*, overpowers the weight *k* and opens the valve *h*, the hole *m* being at the same time closed by the valve *o* (Fig. 2). The boiler is fed, and the flow of steam from the float-chamber *b* to the feed conduit *y* is prevented by the valve *o*. When the lower orifice of the pipe *n* has been sealed again, the steam in the float chamber condenses, and water flows to said chamber from the feed-valve chamber through a pipe *p* containing an anti-return valve *q*. The float chamber is, therefore, not dependent on the pipe *n* for re-filling, as in previously designed feed-water regulators of this type. The provision of the pipe *p* accelerates the filling of the float-chamber, by affording direct flow from the feed-valve to said chamber, and also by supplying cold or comparatively cold water, which accelerates condensation of the steam in the float chamber and causes a vacuum to accelerate the flow. Moreover, the rise from the feed-valve to the float chamber is much less than from the boiler to said chamber. Instead of providing a pipe *p*, the floor of the float chamber may be provided with a hole controlled by an anti-return valve, as shown at *l*, *s*, *r* in Fig. 4. The feed-valve is of course closed again by the weight *k*, when the cup *a* is floated by the water entering the float chamber.

What I claim as my invention and desire to secure by Letters Patent of the United States is:—

1. In a feed-water regulator the combination of a feed-conduit, a feed-valve, float mechanism controlling said feed-valve, said float mechanism comprising a float chamber having a discharge orifice leading to said feed-conduit, and a second valve operative in conjunction with the feed-valve so that said second valve closes said discharge-orifice when the feed valve is opened.

2. In a feed-water regulator the combination of a feed-conduit, a feed-valve having a rod, a feed-valve casing communicating with said feed-conduit, float mechanism controlling said feed-valve and comprising a float-chamber having a discharge-orifice which leads into said casing and through which said valve rod extends into said float chamber, and a second valve on said rod positioned to close said discharge orifice when the feed valve is open.

3. In a feed-water regulator the combination of a feed-valve, a feed-conduit, float mechanism controlling said feed-valve, said float-mechanism comprising a float-chamber having an inlet orifice and a discharge orifice leading to said feed-conduit, an anti-return valve permitting flow of water from said feed-conduit through said inlet orifice, and a valve operative in conjunction with

the feed valve to close said discharge orifice 10 when the feed-valve is open.

In witness whereof I have signed this specification in the presence of two witnesses.

MARTIN ELKOFER.
